OSCILLOSCOPE AMPLIFIER

Hans W. G. Salinger, Fort Wayne, Ind., assignor,
by mesne assignments, to Farnsworth Research
Corporation, a corporation of Indiana

Application February 15, 1945, Serial No. 578,027

8 Claims. (Cl. 315—18)

1

This invention relates to cathode ray oscilloscopes, and particularly to an oscilloscope amplifier for amplifying an input signal to produce visual indications of the signal including its direct current component.

A conventional oscilloscope is usually provided with two pairs of deflecting plates or coils, one being connected to a sweep generator to periodically deflect the cathode ray beam across the screen of the oscilloscope, and the other to a signal source to trace a pattern on the screen which is representative of the input signal. In most cases the input signal does not have sufficient strength to effect deflection of the cathode ray beam which traces the pattern on the screen. Therefore, it is customary to provide a conventional vacuum tube amplifier for amplifying the input signal. However, amplifiers of this type do not pass the direct current component or the average value of the signal to be amplified. This limits seriously the field of application of a cathode ray oscilloscope. Frequently, it is desirable to obtain visual indications of a signal including its average value. This is particularly true when it is desired to check the performance of television equipment by means of a cathode ray oscilloscope.

It has, for instance, been found that the response of a television picture signal generating tube of the light storage type is not directly proportional to the intensity of the light falling on the photosensitive cathode of the tube. When the light intensity increases, the signal output falls off. For investigating this phenomenon it is very desirable to utilize a cathode ray oscilloscope which will produce a visual indication of the signal output of the pickup tube including its direct current component.

Vacuum tube amplifiers are known which will pass direct current but they are difficult to adjust, are unstable, have a limited power output and their internal resistance depends upon the load.

It is an object of the present invention, therefore, to provide an amplifier for a cathode ray oscilloscope which will amplify an input signal to produce a visual indication on the screen of the oscilloscope which is representative of the input signal including the average value thereof.

In accordance with the present invention there is provided the combination of a cathode ray tube comprising a screen and an electron gun for developing an electron beam and focusing it upon the screen. A sweep generator is connected to a first pair of deflectors for deflecting the electron beam across the screen in a predetermined direction. An electron multiplier is provided which

2

includes a plurality of secondary emissive multiplying stages and an electron source for supplying electrons to the first multiplying stage. Further means are provided for controlling the flow of electrons through the multiplier in accordance with an input signal. Finally, means are provided for coupling the output of the multiplier to a second pair of deflectors forming part of the cathode ray tube. Thus, the electron beam of the cathode ray tube is deflected across the screen to trace a pattern which is representative of the input signal and of its average value.

In accordance with a further feature of the invention the electron multiplier which includes a plurality of secondary emissive multiplying stages is associated with means for collecting the electrons from the last multiplying stage. Means are provided for coupling the electron collecting means and the last multiplier stage to a pair of deflectors to provide a push-pull connection. Hence, the pair of deflectors generates a symmetrical electron deflecting field which prevents defocusing of the electron beam of the cathode ray tube.

For a better understanding of the invention, together with other and further objects thereof, reference is made to the following description, taken in connection with the accompanying drawing, and its scope will be pointed out in the appended claims.

In the accompanying drawing:

Fig. 1 is a circuit diagram of a cathode ray oscilloscope and an associated electron multiplier embodying the present invention;

Fig. 2 is a curve representing a saw-tooth voltage wave referred to in explaining the operation of the invention; and

Fig. 3 is a circuit diagram similar to Fig. 1 and embodying a modification of the invention.

Referring now more particularly to Fig. 1 of the drawing there is provided a cathode ray oscilloscope 1 having an evacuated envelope 2 and an electron gun 3 disposed therein. Electron gun 3 comprises cathode 4, which may be indirectly

heated as shown, control grid 5, first anode 6 and second anode 7. Electron gun 3 serves for developing an electron beam, directing and focusing it upon luminescent screen 8, usually referred to as a fluorescent screen and arranged on the inner surface of envelope 2 opposite gun 3. A pair of deflecting plates 9, 10 is provided for deflecting the electron beam across screen 8 in accordance with an input signal. A second pair of deflecting plates 11, 11 is provided in envelope 2 and are ranged at right angles with respect to plates 9, 10.

For the purpose of deflecting the electron beam periodically across screen 8 deflecting plates 11 are connected to sweep generator 12.

Electron multiplier 15 is provided for amplifying an input signal which is then connected across deflecting plates 9, 10 for deflecting the electron beam at right angles to the periodical deflection of the beam effected by sweep generator 12 and deflecting plates 11. Electron multiplier 15 comprises cathode 16, which may be indirectly heated as shown, and control grid 17 for controlling the number of electrons directed into first multiplier stage 18. Electron multiplier 15 comprises further multiplier stages 20, 21, 22, 23 and 24 and electron collector 25.

For the purpose of supplying operating potentials to the electrodes of cathode ray oscilloscope 1 as well as to the multiplier stages of electron multiplier 15 there is provided a common source such, for example, as battery 26 connected across voltage divider 27 and having its negative terminal grounded. Leads 28 and 30 connect cathode 4 of oscilloscope 1 and cathode 16 of multiplier 15, respectively, to a tap on potentiometer 27 to keep them at a potential that is slightly positive against ground. Grid 5 of oscilloscope 1 is connected to ground as shown, while grid 17 of multiplier 15 is connected through lead 31 and resistor 32 to potentiometer 27 for keeping it at a potential that is negative against that of cathode 16. Multiplier stages 18, 20, 21, 22, 23 and 24 are connected to potentiometer 27 in such a manner that each multiplier stage is kept at a higher positive potential than the preceding stage.

First anode 6 of oscilloscope 1 is connected to potentiometer 27 through lead 33 and is maintained at a potential which is positive against cathode 4. Second anode 7 is kept at a potential which may be considerably more positive than that of anode 6 by means of lead 34 connected to potentiometer 27. Leads 35 connecting deflecting plates 11 to sweep generator 12 are shunted by resistor 36 having a center tap connected to lead 34. Lower deflecting plate 9 is also connected to lead 34, while upper deflecting plate 10 is connected through lead 37 to electron collector 25. Electron collector 25 is supplied with positive potential through leads 34, 38 and load resistor 40 which may be adjustable as shown. The input signal is applied across terminals 41, 41, one being connected to ground and the other one to lead 31 connected to control grid 17.

The operation of oscilloscope 1 is conventional and, therefore, no detailed explanation is necessary here. The electron beam developed by gun 3 and focused on screen 8 is deflected in two directions at right angles to each other in accordance with the signal applied to deflecting plates 9, 10 and in accordance with periodically recurring voltages developed by sweep generator 12 to provide a time base for the input signal.

Cathode 16 of electron multiplier 15 serves as an electron source, and the primary electrons provided thereby are attracted by first multiplier stage 18 where they liberate secondary electrons which in turn impinge upon multiplier stage 20. In this manner the primary electron flow is multiplied in successive multiplier stages and finally collected by electron collector 25. The number of primary electrons impinging upon first multiplier stage 18 is controlled by control grid 17 in accordance with the input signal connected across input terminals 41. Electron multiplier 15 am-

plifies the input signal including any direct current component or the average value thereof.

Voltage variations representative of the amplified input signal are developed across load resistor 40 and, thus, the voltage supplied to deflecting plates 9, 10 varies in accordance with the input signal to effect a corresponding deflection of the electron beam. In this manner a pattern is traced on screen 8 with the frequency of sweep generator 12 providing a time base to give a visual indication representative of the amplified signal. It should be noted that deflecting plates 9, 10 and 11, 11 have the same mean potential as second anode 7, as will be seen from an inspection of the drawing.

Supposing the input signal is a saw-tooth voltage wave such as illustrated in Figure 2 at 42. When an oscilloscope with a conventional amplifier is used for visually reproducing voltage wave 42, it is not possible to distinguish whether the zero or reference potential is represented by dotted line 43 or by full line 44. However, since the oscilloscope amplifier of the invention will pass the average value of the input signal it is now possible to distinguish whether the zero potential of voltage wave 42 is at 43 or at 44.

Referring now to Fig. 3 in which like components are designated by the same reference numerals as were used in Fig. 1, it will be seen that cathode ray oscilloscope 1 and multiplier 15 are identical with the structure shown in Fig. 1. The main difference between the circuit of Fig. 3 and the circuit of Fig. 1 is that deflecting plates 9, 10 are now connected in push-pull fashion across electron collector 25 and the last electron multiplier stage 24. To this end multiplier stage 24 is connected to a tap of potentiometer 27 through lead 45 and load resistor 46. Deflecting plate 9 is connected to a variable tap of resistor 46 through lead 47 and battery 48 having its positive terminal connected to deflecting plate 9. Electron collector 25 is maintained at a potential that is positive with respect to that of multiplier stage 24 through lead 50 and load resistor 51. Deflecting plate 10 is connected through lead 52 to a variable tap of load resistor 51 and, thus, to electron collector 25. Shunt resistor 36, connected across leads 35, is connected through a center tap to second anode 7 in the same manner as explained in connection with Fig. 1.

The signal polarity obtained from the electron collector of a multiplier is opposite from that obtained from the last stage of the multiplier. This is so because the last multiplier stage is an electron source, while the collector is an electron sink. Thus, by connecting deflecting plates 9 and 10 to multiplier stage 24 and electron collector 25, respectively, a push-pull connection is obtained. Hence, the lines of force generated by the electric field produced by the signal connected to deflecting plates 9 and 10 are symmetrical, and the symmetrical deflecting field prevents defocusing of the electron beam. Battery 48 is provided for maintaining both deflecting plates 9 and 10 at the same mean potential, which is that supplied by lead 50 connected to potentiometer 27 and to second anode 7. The electron beam may be centered by adjusting the taps on resistors 46 and 51. Otherwise, the oscilloscope and multiplier combination illustrated in Fig. 3 operates in the same manner as explained in connection with Fig. 1.

It is to be understood that one or both pairs of deflecting plates 9, 10 and 11, 11 may be re-

placed by deflecting coils to effect deflection of the electron beam in two directions at right angles to each other. Oscilloscope 4 may also be used with two different input signals which may be connected to deflecting plates 9, 10 and 11, 11, in which case both input signals may be amplified by electron multipliers. In this case sweep generator 42 can be dispensed with. It will also be obvious that any type of voltage-controlled electron multiplier may be used for amplifying the input signal connected to deflecting plates 9, 10.

While there has been described what are at present considered the preferred embodiments of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. The combination of a cathode ray tube comprising a target, means for developing an electron beam of substantially constant intensity and focusing it upon said target, a pair of deflectors for deflecting said beam, an electron multiplier including a plurality of secondary emissive multiplying stages, an electron source for supplying electrons to the first of said multiplying stages, means for controlling the flow of electrons through said multiplier in accordance with an input signal, and means for coupling the output of said multiplier to said pair of deflectors, thereby to obtain an indication representative of said input signal and of its average value.

2. The combination of a cathode ray tube comprising a screen, an electron gun for developing an electron beam of substantially constant intensity and focusing it upon said screen, a first pair of deflectors, a sweep generator connected to said first pair of deflectors for deflecting said electron beam across said screen in a predetermined direction, a second pair of deflectors for deflecting said beam, an electron multiplier including a plurality of secondary emissive multiplying stages, an electron source for supplying electrons to the first of said multiplying stages, means for controlling the flow of electrons through said multiplier in accordance with an input signal, and means for coupling the output of said multiplier to said second pair of deflectors, thereby to produce a visual indication representative of said input signal and of its average value.

3. The combination of a cathode ray tube comprising a screen, an electron gun for developing an electron beam of substantially constant intensity and focusing it upon said screen, a pair of deflectors for deflecting said beam, an electron multiplier including a plurality of secondary emissive multiplying stages, an electron source for supplying electrons to the first of said multiplying stages, means for controlling the flow of electrons through said multiplying stages in accordance with an input signal, means for collecting the electrons from the last one of said multiplying stages, and means for coupling said collecting means to said pair of deflectors, thereby to obtain an indication representative of said input signal and of its average value.

4. The combination of a cathode ray tube comprising a luminescent screen, an electron gun for developing an electron beam of substantially constant intensity and focusing it upon said screen, a first pair of deflectors, a sweep generator connected to said first pair of deflectors for deflect-

ing said electron beam across said screen in a predetermined direction, a second pair of deflectors for deflecting said beam, an electron multiplier including a plurality of secondary emissive multiplying stages, means for supplying operating voltages to said stages, an electron source for supplying electrons to the first of said multiplying stages, means for controlling the flow of electrons through said multiplier in accordance with an input signal, means for collecting the electrons from the last one of said multiplying stages, and means for coupling said collecting means to said second pair of deflectors, thereby to trace a pattern on said screen representative of said input signal and of its average value.

5. The combination of a cathode ray tube comprising a screen, an electron gun for developing an electron beam and focusing it upon said screen, a pair of deflectors for deflecting said beam, an electron multiplier including a plurality of secondary emissive multiplying stages, means for supplying progressively increasing operating voltages to said stages, an electron source for supplying electrons to the first of said multiplying stages, means for controlling the flow of electrons through said multiplier in accordance with an input signal, means for collecting the electrons from the last one of said multiplying stages, and means for coupling said collecting means and said last multiplier stage to said deflectors, thereby to obtain an indication representative of said input signal and of its average value.

6. The combination of a cathode ray tube comprising a luminescent screen, an electron gun for developing an electron beam and focusing it upon said screen, a first pair of deflectors, a sweep generator connected to said first pair of deflectors for deflecting said electron beam across said screen in a predetermined direction, a second pair of deflectors for deflecting said beam, an electron multiplier including a plurality of secondary emissive multiplying stages, means for supplying progressively increasing operating voltages to said stages, an electron source for supplying electrons to the first of said multiplying stages, means for controlling the flow of electrons through said multiplier in accordance with an input signal, means for collecting the electrons from the last one of said multiplying stages, means for coupling said collecting means and said last multiplier stage individually to each one of said second pair of deflectors, and means for adjusting the normal and undeflected position of said electron beam on said screen, thereby to trace a pattern on said screen representative of said input signal and of its average value.

7. The method of producing a visual indication of an input signal on the target of a cathode ray tube, said method comprising developing an electron beam and focusing it on said target, generating a flow of electrons, multiplying said electron flow, controlling the intensity of said electron flow in accordance with said input signal, and deflecting said electron beam across said target in accordance with said multiplied electron flow representative of the instantaneous and average values of said input signal.

8. The method of producing a visual indication of an input signal on the luminescent screen of a cathode ray tube, said method comprising developing an electron beam and focusing it on said screen, deflecting said electron beam periodically across said screen in a predetermined direction, generating a flow of electrons, multiplying said

electron flow by secondary electron emission, controlling the intensity of said electron flow in accordance with said input signal, collecting the multiplied electrons, deriving an output signal from the collected electron flow representative of said input signal and of its average value, and deflecting said electron beam in a direction substantially at right angles to said predetermined direction across said screen in accordance with said output signal, thereby to trace a pattern on 10 said screen.
